GOLF SCORE INDICATOR

William S. Green, Denver, Colo.

Filed June 17, 1965, Ser. No. 85,791

Term of patent 14 years

(Cl. D34—5)

FIG. 1

FIG. 2

FIG. 3

FIG. 5

FIG. 4

FIG. 1 is a front face view of a golf score indicator showing my new design;

FIG. 2 is an end view thereof;

FIG. 3 is a rear view thereof;

FIG. 4 is an enlarged cross-sectional view, taken on the line 4—4, FIG. 1; and

FIG. 5 is an enlarged fragmentary face view of the upper left portion of the face of FIG. 1.

The dominant features of my design reside in the full line portions shown.

I claim:

The ornamental design for a golf score indicator, as shown and described.
